UNITED STATES PATENT OFFICE

HERMAN L. KEUN, OF CHICAGO, ILLINOIS

CENTRIFUGAL PUMP

Application filed September 23, 1927. Serial No. 221,506.

My invention relates to improvements in centrifugal pumps, and it consists in the combinations, constructions, and arrangements herein described and claimed.

5 An object of my invention is to provide a centrifugal pump in which roller bearings and lubricating oil for the bearings may be used, and in which means is provided for eliminating all possibility of the lubricating oil coming in contact or mixing with liquid passing through the pump.

A further object is to provide a centrifugal pump in which the liquid passing through the pump is first passed through opposing 15 ports in a rotor and deflected to a common center, thus eliminating end motion of the rotor.

A further object is to provide a centrifugal pump in which the liquid entering the pump 20 is fed into the eye of the impeller under a positive pressure, thus greatly enhancing the efficiency of the pump.

A further object is to provide a centrifugal pump in which the customary packing is dispensed with, and in which suitable wear-compensating rings are employed so as to make 25 a perfect liquid or air-tight device.

A further object is to provide a centrifugal pump in which a part of the liquid passing 30 through the pump acts as a cushion for the rotor, thus eliminating vibration, reducing friction, and at the same time using a part of the liquid as a lubricant where it is not desirable to employ lubricating oil.

35 A further object is to provide a centrifugal pump in which the impeller unit may be reversed in the housing, thereby changing the function of the device from a centrifugal pump to a liquid turbine engine suitable for 40 receiving energy from liquid passed through the device under compression, and transmitting the energy derived from such liquid under compression to driving any suitable mechanism.

45 A further object is to provide a centrifugal pump in which the rotor revolves in a space filled with liquid and the confines of which converge on two sides to a given point, thereby reducing circular velocity.

50 A further object is to provide a centrifugal

pump having relatively few parts, and the parts of which may be easily and quickly assembled or disassembled.

Other objects and advantages will appear in the following specification, and the novel features of the invention will be particularly pointed out in the appended claims.

55 My invention is illustrated in the accompanying drawings, forming part of this application, in which

60 Figure 1 is a central longitudinal sectional view through my device,

65 Figure 2 is a sectional view taken along the line 2-2 of Figure 1,

Figure 3 is a sectional view taken along the line 3-3 of Figure 2, and

65 Figure 4 is a top plan view of the device shown in Figure 2.

In carrying out my invention, I provide a 70 casing comprising a base portion 1 and a cover portion 2. The base portion 1 and the cover portion 2 are provided with flanges 3 and 4 which are firmly secured together by means of bolts 5, see Figures 2 and 4. Referring to Figure 1, it will be observed that the base portion 1 and the cover portion 2 are provided with extended portions 6 and 7. Suitable roller bearings 8 and 9 are disposed within recesses 10 and 11 in the extended portions 6 and 7.

75 A rotor R is mounted for rotation between the bearings 8 and 9. The rotor in the present instance consists of two sections 12 and 13. An impeller I is formed integral with the sections 12 and 13, that is, a flange portion 14 is cast integral with the section 13 and a flange portion 15 is cast integral with the section 12. Vanes 16 and 17 are cast integral with one of the flanges 14 or 15 so that the flanges are held in spaced relation and are firmly riveted together by means of rivets 18, 80 see Figure 2. It will now be seen that the rotor R consisting of the sections 12 and 13 and the impeller I consisting of the flanges 14 and 15 are riveted or otherwise secured together so that the rotor and the impeller 85 form a unit.

85 The rotor R is provided with a reduced portion 19 upon which a cone 20 is mounted. The reduced portion 19 is provided with 90

95 100

threads 21 to receive a nut 22, see Figure 1. The nut 22 bears against the cone 20, thus holding the roller bearings 9 firmly in place. The extended portions 6 and 7 are provided with an annular recess 23 to receive a flange 24 integral with a protecting cap 25. Screws 26 passing through the flange 24 firmly hold the protecting cap 25 in position. While the protecting cap 25 is primarily for the purpose of protecting the roller bearings 9 from dirt and other elements which may cause damage thereto, it also serves as a means for retaining lubricating oil within the recess 11 of the roller bearings 9.

15 Referring again to Figure 1, it will be noted that the section 12 of the rotor R is provided with a reduced portion 27 having threads 28 to receive a nut 29 which bears against a cone 30 forming a part of the roller bearings 8. A cup 31 bears against a shoulder 32 within the recess 10. Since the cup 31 bears against the shoulder 32 and the nut 29 against the cone 30, it will be seen that the roller bearings 8 are firmly secured in place. The extended portions 6 and 7 are provided with a recess 33 within which an oil retaining ring 34 is disposed and held in position by means of screws 35. A shaft 36 upon which a suitable driving pulley or gear 30 may be mounted is formed integral with the reduced portion 27.

35 A central chamber 37 is provided in the cover portion 2 and the base 1. Referring to Figure 2, it will be seen that the central chamber 37 converges so as to form a relatively narrow space 38 between the walls of the chamber and the rotor R. The purpose of this will be explained later. Referring now to Figure 1, it will be noted that I have provided annular grooves 39 in the base portion 1 and the cover portion 2. A sleeve 40 is disposed within each of the grooves 39 and is held against rotation by means of pins 41 embedded in the base portion 1 and projecting into the sleeves. Suitable expanding piston type rings 42 are disposed within peripheral grooves 43 which are cut around the rotor R. The base portion 1 and the cover portion 2 are provided with annular recesses 44 within which sleeves 45 are disposed and held against rotation by means of pins 46 passing into the base portion 1. The sleeves 45 are provided with flanges 47 which are disposed within recesses 48. Each of the sleeves 45 is provided with a groove 49 for the purpose of permitting liquid to pass therethrough and into contact with the piston type rings 42 which are in contact with the two sleeves 45.

55 60 The base portion 1 and the cover portion 2 are provided with a gradually widening and rounding outlet 50, see Figure 2. A liquid inlet 51 is provided in the base portion 1. The inlet 51 is separated to form passageways 52 and 53, see Figure 1. The pas-

55 60 65 70 sageways 52 and 53 pass along the sides 54 and 55 forming the outlet 50, see Figure 1. The passageways 52 and 53 are slightly narrowed at 56 at points adjacent the rotor R, as shown in Figure 1.

75 80 85 A central chamber 57 is provided within the rotor R, see Figures 1 and 2. Inlet ports 58 are provided at both ends of the rotor R. These ports, as will be seen from Figures 1 and 2, are provided with concave faces 59 having edges 60 adapted to cleave the liquid passing through the ports and forcing it inwardly. It will further be seen that the ports 58 are cut angularly so as to deflect liquid passing therethrough toward the center of the chamber 57, that is, the liquid entering each end of the rotor R is deflected to a common center, as will be more fully explained later.

90 95 100 Referring to Figure 1, it will be seen that the sides of the impeller I are spaced away from the side portions 54 and 55 forming the outlet 50, thereby eliminating a certain amount of friction as well as danger of small particles wedging between the impeller and the walls. The central chamber 57 is reduced slightly at 61 to provide additional material for a greater strength in the rotor at a point adjacent the shaft 36 to which power is applied. The outlet 50 is provided with flanges 62, see Figures 1 and 2. The flanges 62 protect the impeller I from frictional contact with the liquid passing through the outlet 50, thus reducing to a minimum the friction between the impeller and the liquid passing through the outlet 50.

105 110 115 From the foregoing description of the various parts of the device, the operation thereof may be readily understood. Assuming that the pump has been primed and power applied so that the rotor R and the impeller I are rotating at the necessary speed,

120 125 liquid will be drawn inwardly through the inlet 51 separating and passing into the passageways 52 and 53 and into the chamber 37 surrounding the rotor R. As the liquid enters the chamber 37, it will be noted from Figure 2 that the converging chamber 37 forces the liquid against the rotor at points adjacent the ports 58 at which time the edges 60 will cleave the liquid and discharge it within the chamber 57. As the liquid passes through the ports 58, it will be deflected toward the center of the chamber 57 and delivered into the eye of the impeller I under a positive pressure. It will be observed that liquid passing through the ports 58 from each end of the rotor R will be discharged into the chamber 57 in a converse direction to the motion of the liquid already within the chamber, thus preventing the liquid entering the chamber from instantly attaining or developing a centrifugal force until substantially reaching the eye of the impeller. The liquid enters the eye of the impeller 130

under a positive pressure, thereby eliminating the necessary suction or replacement functions of the usual impeller construction, and thus permitting the impeller to impart compression and centrifugal force alone.

5 When once the liquid has entered the eye of the impeller, it is taken up by the vanes 16 and 17 and discharged into the outlet 50 where it is passed into a discharge nozzle 63. The outlet 50 enlarges gradually so as to provide for the continually increasing volume of water discharged from the impeller.

10 It will be seen that I have provided a device in which the rotor and the impeller are supported by means of the roller bearings, thus 15 reducing to a minimum the resistance between moving parts. Also in equipping my device with expanding rings of the piston type, any wear between the rings 42 and the sleeves 40 and 45 is automatically taken up by the expanding rings.

15 The rotor or impeller unit may be reversed in the housing or base 1 and the cover portion 2, thereby converting the centrifugal pump 25 into a liquid turbine engine capable of receiving energy from liquid under compression and transmitting it to the shaft 36.

20 Suitable pins 64 anchor the rings 42 to the rotor R so that the rings are caused to rotate with the rotor.

25 I claim:

1. A centrifugal pump comprising a casing having a central chamber, inlet ports and an outlet port, a rotor having a chamber and a plurality of ports and disposed within said central chamber in said casing, sealing means mounted upon said rotor, sleeves disposed within the central chamber in said casing and arranged to bear against said sealing means, 35 an impeller secured to said rotor, said impeller having vanes communicating with the chamber within said rotor, and bearing means for rotatably mounting the rotor and said impeller within said casing.

40 2. A centrifugal pump comprising a casing having a central chamber, liquid inlet ports, and a liquid outlet port, a rotor having a chamber and a plurality of angularly-disposed ports communicating with said liquid inlet ports and said chamber within the rotor, an impeller, said impeller being provided with a plurality of vanes arranged to discharge the liquid passing through said liquid inlet ports and said angularly-disposed ports 50 in the rotor and said second named chamber into said liquid outlet port, and bearing means for rotatably mounting the rotor and said impeller within the chamber in said casing.

45 3. In a centrifugal pump, a casing having a central-chamber, an inlet port and an outlet port, a rotor having a chamber and a plurality of angularly disposed ports communicating with said inlet port, a plurality of sealing rings mounted upon said rotor, a plural-

ity of sleeves mounted within the chamber in said casing and arranged to bear against said sealing rings, an impeller carried by the rotor, bearing means arranged for rotatably mounting the rotor and said impeller, and means for enclosing said bearing means.

50 4. A centrifugal pump having a casing comprising a base portion and a cover portion provided with a central chamber, inlet ports, and an outlet port spirally-disposed with respect to said central chamber, a rotor disposed within said central chamber and having a chamber and a plurality of angularly-disposed ports having concave faces, said angularly-disposed ports communicating with said inlet ports and the chamber within said rotor, an impeller carried by the rotor, vanes disposed within the impeller and communicating with the chamber within the rotor and said spirally-disposed outlet port, and bearing means for rotatably mounting the rotor and said impeller within the central chamber in said base portion and said cover portion.

55 5. A centrifugal pump having a casing comprising a base portion and a cover portion provided with a central chamber, inlet ports, and an outlet port spirally-disposed with respect to said central chamber, said base portion and said cover portion being provided with flanges, means passing through said flanges for securing the base portion and said cover portion together, a rotor disposed within said central chamber and having a chamber and a plurality of angularly-disposed ports having concave faces, said angularly-disposed ports communicating with said inlet ports and the chamber within said rotor, an impeller carried by the rotor, vanes disposed within the impeller and communicating with the chamber within the rotor and said spirally-disposed outlet port, bearing means for rotatably mounting the rotor and said impeller within the central chamber in said base portion and said cover portion, and means for enclosing said bearing means.

60 6. A centrifugal pump comprising a casing having a chamber and an inlet port and an outlet port, a rotor disposed within said chamber and being provided with a chamber and a plurality of angularly disposed ports having concave faces, said angularly disposed ports being in communication with said inlet port and the chamber within said rotor, and an impeller carried by the rotor.
